Specification for Design.

Patented July 27, 1915.

Application filed June 4, 1915. Serial No. 32,219. Term of patent 3½ years.

To all whom it may concern:

Be it known that I, FRITZ RAU, a citizen of the Republic of Switzerland, residing at St. Gallen, Switzerland, have invented a new, original, and ornamental Design for Embroidered Trimming, of which the following is a specification, reference being had to the accompanying drawing, forming a part thereof.

The figure is a plan view of a portion of the trimming, showing my new design.

I claim:

Copies of this patent may be obtained for five cents each, by addressing the "Commissioner of Patents, Washington, D. C."

The ornamental design for embroidered trimming, as shown.

In testimony whereof I have signed this specification in the presence of two subscribing witnesses.

FRITZ RAU.
